UNITED STATES PATENT OFFICE.

TIMOTHY HAYES DONOVAN, OF RAYMOND, WASHINGTON, ASSIGNOR OF ONE-HALF
TO RALPH GERBER, OF RAYMOND, WASHINGTON.

UNLOADING APPARATUS.

1,094,060.

Specification of Letters Patent. Patented Apr. 21, 1914.

Application filed March 5, 1913. Serial No. 752,132.

To all whom it may concern:

Be it known that I, TIMOTHY H. DONOVAN, a citizen of the United States, residing at Raymond, in the county of Pacific and State 5 of Washington, have invented certain new and useful Improvements in Unloading Apparatus, of which the following is a specification.

The apparatus which is the subject of the 10 present invention is designed for unloading logs from logging cars, and its object is to provide an apparatus which is rapid in operation and which can be controlled without danger of injury to the operator.

15 The apparatus consists in a horizontal sweep which is so located with respect to the car that its arms swing in an arc crossing the car, so that when the free end of one of said arms is placed against the load and 20 the car is moved forward, the load is pushed laterally off the car.

In order that the invention may be better understood, reference is had to the accompanying drawings in which—

25 Figure 1 is an elevation of the apparatus; Fig. 2 is a plan view thereof, and Fig. 3 is a vertical section on the line 3—3 of Fig. 2.

Referring specifically to the drawings, 5 denotes a piling arranged in a square and 30 braced on the top by planks 6, and on the sides by planks 7. In the center of the piling is an upright post 8 firmly secured to the piles 5 by suitable braces 9. The post and 35 piles are securely anchored by being driven into the ground a suitable distance.

Pivoted suspended from the top of the post 8 is a four-armed revolving sweep, the arms 10 of which are horizontal and swing in a horizontal plane. The arms are rigidly 40 connected at their inner ends by angle-plates 11, said ends being spaced from the post 8. The arms are also connected by diagonal brace rods 12, one of which latter is provided with a turnbuckle 13. The arms 45 are further braced and supported from the top of the post 8 by means of crossed plates 14 and rods 15 extending from the latter and through stirrups 16 at the top and bottom of the arms adjacent to the inner ends 50 thereof. The arms 10 are connected in pairs by means of cables 17 secured to the arms near their outer or free ends. On the top plate 14 are firmly mounted two pulleys 18 arranged at right angles to each other and 55 one above the other, over which pulleys the

cables pass. The arms are thus connected in pairs the members of which are diametrically opposite each other. One of the cables passes over one of the pulleys, and the other cable passes over the other pulley.

At the top of the post 8 is a cap 19 having its upper surface slightly convex. Between the cap and the bottom plate 14 may be placed a wear plate 20.

In the top of the post 8 is embedded a 65 pivot 21 on which the sweep turns, which pivot passes through the cap 19 and rises a sufficient distance therefrom so that it may pass through the plate 20, and the bottom plate 14, and have a bearing in the top plate 70 14. The sweep loosely encircles the post 8, and the arms 10 are thus allowed a limited up and down motion as indicated by dotted lines in Fig. 1. A semi-circular buffer 22 is removably attached to one side of the post 8. 75

Around the outer end of each arm 10 is attached, by bolts 23 and a strap 24, a plate 25 extending across the end of the arm and having thereat a series of sharp points 26 to engage the logs to be unloaded. Each arm 80 10 is provided near its outer end with a suitable handle 27 to facilitate the adjustment of the arm into operative position.

The herein-described apparatus is located adjacent to one side of the track 28 on which 85 the cars 29 to be unloaded stand, and the length of the sweep-arms 10 is such that their free ends swing in an arc crossing the car.

The operation of the apparatus is as follows: A car of logs is pushed over the 90 track when one of the sweep-arms 10 extends at an acute angle to the track, as shown by dotted lines in Fig. 2. The operator stands on one side of the track grasping the handle 27, and at some suitable point 95 on the side of the log nearest to him he pushes the arm over and engages the points 26 with the log. As the car moves on the arm swings around, and the end which engages the log swings in an arc crossing the 100 car so that the logs are pushed off the car laterally, in a line approximately parallel to the track, and fall into the boom below. The forward movement of the car brings the next sweep-arm in position to unload 105 the next car, and so on until the entire train of cars has been unloaded. When the sweep-arm is at a right angle to the track it extends entirely across the car so that it clears the latter of any logs inclined to stick. 110

The apparatus affords absolute safety to the operator and it is rapid in operation. The vertical motion of the sweep-arms hereinbefore described allows the operator greater liberty of action in choosing the proper place of engagement with the log. The apparatus also prevents damage to the cars, the steady pushing motion preventing the fall of the top logs on the edge of the car. By connecting the sweep-arms in pairs the vertical adjustment thereof to engage the log is rendered easy as the arm which is to be adjusted is balanced by its connection through the cable 17 with the diametrically opposite arm.

I claim:

1. An apparatus for unloading vehicles comprising a vertically adjustable horizontal sweep-arm engageable at its outer end with one side of the load, and mounted to swing in an arc crossing the vehicle.
2. An apparatus for unloading vehicles comprising a pivoted sweep having diametrically opposite horizontal arms mounted to swing in an arc crossing the vehicle and successively engageable at their outer ends with one side of the load.
3. An apparatus for unloading vehicles comprising horizontal sweep-arms engageable with the load on one side thereof and mounted to swing in an arc crossing the vehicle, said arms being vertically adjustable and connected in diametrically opposite pairs to balance each other.
4. An apparatus for unloading vehicles comprising a post, a sweep pivotally suspended from the top of the post, said sweep having horizontal arms mounted to swing

in an arc crossing the vehicle, and said arms being loose to permit vertical adjustment at their free ends, pulleys mounted at the top of the post, and cables passing over said pulleys, and connecting diametrically opposite ones of the arms.

5. An apparatus for unloading vehicles comprising a post, a support pivotally mounted at the top of the post, horizontal sweep-arms fastened together and suspended from the aforesaid support, pulleys carried by the support, and cables passing over said pulleys and connecting diametrically opposite ones of the arms.

6. An apparatus for unloading vehicles comprising a post, a support pivotally mounted at the top of the post, horizontal sweep-arms fastened together, suspension means connecting the inner ends of the arms to the support, and suspension means between the support and the outer ends of the arms.

7. An apparatus for unloading vehicles comprising a post, a support pivotally mounted at the top of the post, horizontal sweep-arms fastened together, suspension means connecting the inner ends of the arms to the support, pulleys carried by the support, and cables passing over said pulleys and connected to diametrically opposite ones of the arms at the outer ends thereof.

In testimony whereof I affix my signature in presence of two witnesses.

TIMOTHY HAYES DONOVAN.
